S. B. WILLIAMS, JR

CIRCUIT CONTROLLING APPARATUS

Filed Dec. 18, 1920

Inventor:

Samuel B. Williams, Jr.

by E.R. Nowlan Atty.

UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

CIRCUIT-CONTROLLING APPARATUS.

Application filed December 18, 1920. Serial No. 431,603.

To all whom it may concern:

Be it known that I, SAMUEL B. WILLIAMS, Jr., a citizen of the United States, residing at Brooklyn, in the county of Kings, State of New York, have invented certain new and useful Improvements in Circuit-Controlling Apparatus, of which the following is a full, clear, concise, and exact description.

This invention relates to circuit controlling apparatus, and more particularly, to circuit controlling apparatus for governing the selection of circuits in automatic and semi-automatic telephone systems.

The object of the invention is to provide an improved circuit controlling apparatus in the form of a counting relay circuit arrangement, the improvement consisting in the reduction in the number of relays required to select the circuit corresponding to the number of impulses transmitted by an impulse sender.

To attain the object of the invention, a series of counting relays, less in number than the number of circuits capable of selection thereby, are so arranged as to be successively energized a plurality of times. Cooperating with the counting relays are a plurality of transfer relays which operate at certain stages of the selection to control in conjunction with the counting relays, the selection of the circuit corresponding to the number of impulses transmitted by the impulse sender.

35 The accompanying drawing diagrammatically illustrates one embodiment of the invention. A calling station is shown with means indicated to connect it to a circuit in which the invention resides, and means are indicated for extending the circuit to, and
40 establishing a connection with, one of a plurality of succeeding circuits. For a full explanation of the manner in which the indicated connecting means is operated reference may be had to the Patent No. 1,487,
45 996, granted to S. B. Williams March 25, 1924. The succeeding circuit to the one disclosed in this invention may be as shown in the application of Edward E. Hinrichsen, Serial No. 345,714, filed December 18, 1919,
50 Patent No. 1,463,815, issued August 7, 1923. These references are cited for facilitating an understanding of this invention, but it is not to be understood that the invention is lim-

ited to systems as disclosed in these references.

When the subscriber at substation A removes his receiver from its hook, he causes a line relay (not shown) to become energized in the usual manner, which relay, in turn, causes the energization of the relays 28 and 29. Relay 28 connects the line from substation A to a circuit 25 and the relay 29 connects the circuit 25 to a trunk circuit in which the various functions of a selector switch are performed. The trunk circuit will be referred to by its details, since it occupies practically the whole of the drawing.

Upon the operation of the relays 28 and 29, the line of substation A is connected to the relay 10 which becomes energized through its two windings and the substation loop. Relay 10 in attracting its armature completes an obvious circuit for the energization of relay 11, which is preferably of the slow-to-release type, so as to maintain its armatures attracted during the sending of a series of impulses to relay 10. Relay 11 in attracting its outer left-hand armature places a ground on conductor 21, which ground, in addition to locking the relays 28 and 29, operates cut-off relay 27. Relay 27 in operating serves the well-known purpose of disconnecting the line relay (not shown) from the calling line.

The connection is now ready for the sending of impulses from the calling station A. We will assume that a circuit having the number 4 is desired. The subscriber at station A now actuates the sender S to send four impulses. Each time an impulse is transmitted there will be an interruption of the circuit including relay 10, so that relay 10 retracts its armature momentarily four times.

At the first retraction of the armature of relay 10, relays 12 and 13 operate over a path extending from ground, armature and back contact of relay 10, right-hand armature and front contact of relay 11 and thence in parallel, one path extending through the right-hand winding of relay 12 and resistance 14 to grounded battery, and the other path extending through the winding of relay 13 to grounded battery. Relay 12 in operating locks up through its left-hand winding and contacts under the control of slow-

to-release relay 11. Relay 13 is preferably of the slow-to-release type so as to maintain its armature attracted during the sending of a series of impulses. Relay 13, in operating, extends the conductor 50, through its contacts 41 and the outer right-hand armature and back contact of relay 38, and over conductor 21 to ground at the left-hand contacts of relay 11. At the first retraction of the armature of relay 10, a circuit is prepared for counting relay 30 over a path extending from ground, through the outer left-hand armature and front contact of relay 11, conductor 21, back contact and outer right-hand armature of relay 38, contacts 41 of relay 13, conductor 50, contacts *b* of counting relay 31, winding of counting relays 30, contacts *a* of counting relays 30, 31, 32 and 33, front contact and right-hand armature of relay 12 and thence in parallel one path extending through the right-hand winding of relay 12 and resistance 14 to grounded battery, and the other path extending through the winding of relay 13 to grounded battery. Relay 30 does not operate as long as the normal contacts of relay 10 are closed, due to said relay 30 being short-circuited by ground at the normal contacts of relay 10. When relay 10 operates at the end of the first interruption in the line circuit, the short circuit for relay 30 is removed and it operates over the path previously traced. Relay 30 and all other counting relays are so adjusted that the inner right hand contacts make before contacts *a* and *b* break. Relay 30 in operating locks up over a path extending from ground, outer left-hand armature and front contact of relay 11, conductor 21, back contact and outer right-hand armature of relay 38, contacts 41 of relay 13, conductor 50, contacts *b* of counting relay 31, winding, front contact and inner right-hand armature of counting relay 30 and resistance 14 to grounded battery. Relay 30 in operating also connects through its contact *c* the impulse conductor 51 to the next counting relay, namely counting relay 31.

The windings of relay 12 are so related that the reduction of the current flowing through the righthand winding occurring during the operation of the counting relay 30, causes the release of said relay 12. The relay 12 is thus released in order to prevent the improper operation of the succeeding counting relay 31 before the next impulse is received.

At the second retraction of the armature of relay 10 in response to the second impulse transmitted by the sender S, relay 12 again operates in the circuit traced through its right-hand winding and a circuit is prepared for counting relay 31 over a path extending from ground, outer left-hand armature and front contact of relay 11, con-

ductor 21, back contact and outer right-hand armature of relay 38, contacts 41 of relay 13, conductor 50, contacts *b* of relay 32, winding of counting relay 31, contacts *c* of relay 30, contacts *a* of relays 31, 32 and 33, conductor 51, front contact and right-hand armature of relay 12 and thence in parallel, one path extending through the right-hand winding of relay 12 and resistance 14 to grounded battery and the other path extending through the winding of slow-to-release relay 13 to grounded battery. Relay 31 does not operate as long as the normal contacts of relay 10 are closed due to relay 31 being short-circuited by ground connected to the normal contacts of relay 10. When relay 10 operates at the end of the second interruption in the line circuit, the short circuit for relay 31 is removed and said relay 31 operates over the path previously traced. Relay 31 in operating locks up through its front contact and inner right-hand armature under control of relay 32 and in opening its contacts *b* opens the holding circuit for counting relay 30, thereby causing the release of said relay 30. As above described in connection with the sending of the first impulse, the relay 12 is released during the operation of the second counting relay 31 to prevent the improper operation of the succeeding counting relay 32. It may be noted at this point that the relay 12 releases in this manner during the operation of each succeeding counting relay to prevent the improper operation of said relays.

At the third retraction of the armature of relay 10 in response to the third impulse transmitted by the sender S, relay 12 operates and a circuit is prepared for counting relay 32 over a path extending from ground, outer left-hand armature and front contact of relay 11, conductor 21, back contact and outer right-hand armature of relay 38, contacts 41 of relay 13, conductor 50, contacts *b* of counting relay 33, winding of counting relay 32, contacts *c* of counting relay 31, contacts *a* of counting relays 32 and 33, conductor 51, front contact and right-hand armature of relay 12 and thence in parallel, one path extending through the right-hand winding of relay 12 and resistance 14 to grounded battery, and the other path extending through the winding of relay 13 to grounded battery. Relay 32 does not operate as long as the normal contacts of relay 10 are closed due to said relay 32 being short-circuited at the normal contacts of relay 10. When relay 10 attracts its armature at the end of the third interruption in the line circuit, the short circuit from relay 32 is removed and it operates over the path previously traced. Relay 32 in operating, locks up through its front contact and inner right-hand arm-

ture under control of contacts *b* of counting relay 33 and opens at its contacts *b* the holding circuit for counting relay 31, whereupon said relay 31 releases. Relay 32 in 5 operating transfers impulse conductor 50 through its contacts *c* to counting relay 33, and also causes the release of relay 12.

At the fourth retraction of the armature of relay 10 in response to the fourth 10 impulse transmitted by the impulse sender S, relay 12 operates and a circuit is prepared for counting relay 33 over a path extending from ground, outer left-hand armature and front contact of relay 11, conductor 21, back contact and outer right-hand armature of relay 38, contacts 41 of relay 13, conductor 50, contacts *b* of counting relay 30, winding of counting relay 33, contacts *c* of counting relay 32, contacts 20 *a* of counting relay 33, conductor 51, front contact and right-hand armature of relay 12 and thence in parallel, one path extending through the right-hand winding of relay 12 and resistance 14 to grounded battery, and the other path extending through the winding of relay 13 to grounded battery. Relay 33 in operating locks up over a path including ground on conductor 50, contacts *b* of relay 30, winding, front contact and inner right-hand armature of relay 33 and resistance 14 to grounded battery. Relay 33, in operating, opens at its contacts *b* the holding circuit for counting relay 32, whereupon said relay 32 releases. 30 Relay 33 in operating also completes a circuit for transfer relay 35 over a path extending from grounded battery, winding of relay 35, back contact and outer right-hand armature of transfer relay 34, front contact and outer left-hand armature of relay 33, conductor 50, contacts 41 of relay 13, outer right-hand armature and back contact of relay 38 and front contact and outer left-hand armature of relay 11 to ground. 40 Relay 33 also causes the release of relay 12.

After the fourth impulse has been transmitted by the impulse sender S, the circuit for relay 10 may remain closed, whereupon slow-to-release relay 13 will deenergize due to the circuit therefor being opened at the normal contacts of relay 10. The armature of relay 13 is so adjusted that contacts 40 make before contacts 41 break when relay 13 deenergizes so that relays 60 55 and 61 will be energized over a path extending from ground, outer left-hand armature and front contact of relay 11, conductor 21; back contact and outer right-hand armature of relay 38, contacts 40 of relay 13, inner left-hand armature and front contacts of counting relay 33 and thence in parallel through the intermediate and outer right-hand contacts of transfer relays 60 35 and 37 and through the windings of relays 60 and 61 to grounded battery. Re-

lays 60 and 61 in operating extend the trunk circuit to the succeeding circuit which may be a connector as shown in the disclosure of E. E. Hinrichsen Patent No. 1,463,815 hereinbefore mentioned. Relays 60 and 61 70 in operating may control the energization of a line relay in the connector circuit, whereupon ground may be connected to the conductor 62 in the well known manner thereby causing the energization of cut-off 75 relay 38. Relay 38 in operating disconnects the relay 10 from the calling line and extends ground from the conductor 62 through its right-hand armature and front contact to conductor 21 for the purpose of maintaining cut-off relay 27 and relays 28 and 29 energized. Relay 10 releases when relay 38 operates, causing thereby the release of relay 11. Relay 11 in releasing opens the original circuit for relays 27, 28 and 29. As 80 soon as relay 13 has fully retracted its armatures all relays of the counting relay circuit are restored to normal.

If five impulses had been transmitted by the sender S, relay 10 would have retracted 90 its armature five times. Upon the fifth retraction, a circuit would have again been prepared for counting relay 30 over a path extending from ground, outer left-hand armature and front contact of relay 11, conductor 21, back contact and outer right-hand armature of relay 38, contacts 41 of relay 13, conductor 50, contacts *b* of counting relay 31, winding of counting relay 30, contacts *c* of counting relay 33 and thence over conductor 51 to grounded battery over the path previously traced. Relay 30 does not operate as long as the normal contacts of relay 10 are closed due to relay 30 being short-circuited at the normal contacts of relay 10. 95 When relay 10 operates at the end of the fifth interruption in the line circuit, the short-circuit for relay 30 is removed and it operates over the path previously traced. Relay 30, in operating, opens at its contact 100 *b*, the holding circuit for counting relay 33, whereupon said relay 33 releases. Relay 30 locks up under control of relay 31 over the path previously traced.

At the end of the fifth interruption of the 115 line circuit, and as soon as counting relay 33 releases, the shunt around relay 34 is opened and said relay operates in the following circuit: grounded battery, winding, front contact and inner right-hand armature of transfer relay 35, winding of transfer relay 34, conductor 50, contacts 41 of relay 13 to ground on conductor 21. It will be noted 120 that this circuit is prepared for relay 34 when relay 35 operates at the end of the fourth interruption in the line circuit, but relay 34 does not operate at this time due to its being short-circuited by the direct path to ground on conductor 50, through the outer right-hand contacts of relay 34 and 125 130

contact *b* of relay 33. Transfer relay 34 in operating prepares a circuit for the selection of the circuit No. 5 and if no further impulses are sent, relays in circuit No. 5 corresponding to relays 60 and 61 of circuit No. 4 will be operated due to contacts 40 of relay 13 being connected to ground on conductor 21 when slow-to-release relay 13 releases.

- 10 If six impulses are transmitted by the sender S, relay 10 will retract its armatures six times. At the sixth retraction of the armature of relay 10, a circuit is prepared for counting relay 31 and when relay 10 15 attracts its armature at the end of the sixth interruption in the line circuit, counting relay 31 operates over the path previously traced and in operating releases counting relay 30. Counting relay 31 in operating 20 in conjunction with transfer relays 34 and 36 prepares a circuit for the selection of relays in the circuit No. 6, corresponding to relays 60 and 61 of circuit No. 4, which circuit will be closed if no further impulses 25 are sent due to relay 13 releasing when the line circuit remains closed.

If seven impulses are transmitted by the impulse sender S, relay 10 will retract its armature seven times and upon the seventh 30 retraction of the armature of relay 10, a circuit is prepared for counting relay 32. Counting relay 32 energizes as soon as relay 10 attracts its armature at the end of the seventh interruption in the line circuit and, 35 in operating, locks up under the control of relay 33 and releases counting relay 31. Relay 32 in operating in conjunction with transfer relays 35 and 37 prepares a circuit for the operation of relays in circuit No. 7 40 similar to relays 60 and 61 in circuit No. 4. Relay 13 in releasing after the seven impulses have been transmitted by the sender S, operates relays in circuit No. 7 corresponding to the relays 60 and 61 of circuit 45 No. 4.

If eight impulses are transmitted by the impulse sender S, relay 10 will retract its armature eight times and upon the eighth retraction thereof a circuit is prepared for 50 counting relay 33 over the path previously traced. At the end of the eighth interruption in the line circuit, counting relay 33 operates, thereby releasing the counting relay 32 and completing a circuit for the 55 energization of transfer relay 37 over a path extending from grounded battery, winding of relay 37, back contact and outer right-hand armature of transfer relay 36, front contact and outer right-hand armature of transfer relay 34, front contact and outer left-hand armature of counting relay 33, contacts 41 of relay 13 and thence to ground on conductor 21. Transfer relay 37 60 in operating remains energized over the path traced and in attracting its interme-

diate and outer right-hand armatures prepares a circuit in conjunction with counting relay 33 for the operation of relays in circuit No. 8 similar to the relays 60 and 61 in circuit No. 4, which circuit is completed 70 when relay 13 releases. It will be noted that when relay 37 operates a circuit for the energization of transfer relay 36 is prepared over a path extending from grounded battery, winding, front contact and inner right-hand armature of transfer relay 37, winding of transfer relay 36 and conductor 50 and thence to ground on conductor 21. Relay 36 is short-circuited, however, due to a direct path to ground being present for 75 relay 37 through the outer right-hand contacts of relay 36, outer right-hand alternate contacts of relay 34 and the front contact and outer left-hand armature of counting relay 33. 80

If nine impulses are transmitted by the transmitter S, line relay 10 will retract its armatures nine times. At the ninth retraction of the armature of relay 10, a circuit is prepared for counting relay 30 over a path 85 previously traced. As soon as relay 10 attracts its armature at the end of the ninth interruption of the line circuit, counting relay 30 operates and locks up under control of counting relay 31. Relay 30 in operating 90 opens at its contacts *b* the holding circuit for relay 33, whereupon said relay 33 releases. Relay 33 in releasing removes the short-circuit for transfer relay 36, whereupon said relay 36 operates in series with 100 transfer relay 37 over the path previously traced. Relay 36, in operating in conjunction with transfer relay 34 and counting relay 30, prepares a circuit for the energization of relays in the circuit No. 9 similar to 105 relays 60 and 61 in the circuit No. 4, which relays will be energized as soon as relay 13 retracts its armature.

If ten impulses are transmitted by the sender S, relay 10 will retract its armatures 110 ten times and the counting relay 31 will again be energized over the path previously traced. Counting relay 31 in operating locks up under control of counting relay 32 and releases counting relay 30. Relay 31 in 115 operating in conjunction with transfer relays 34 and 36 prepares a circuit for the energization of relays in circuit No. 10 similar to relays 60 and 61 in circuit No. 4, which relays are operated as soon as relay 120 13 releases.

To release an established connection the calling station A replaces the receiver in the switchhook whereupon ground will be removed from conductor 62 thereby causing 125 the release of all relays locked to this conductor.

What is claimed is:

1. In a telephone system, an impulse sender, a selector comprising a series of 130

- counting relays, a number of selectable lines, means for successively energizing the counting relays a plurality of times, and a plurality of transfer relays cooperating with said counting relays for selecting the line corresponding to the number of impulses transmitted by said sender. 25
6. In a telephone system, an impulse sender, a plurality of link circuits, a series 10 of counting relays less in number than the number of said link circuits, means for energizing one of said relays in response to each impulse transmitted by said sender, means for deenergizing one of said counting 15 relays each time a succeeding relay of the series is energized, and a plurality of transfer relays cooperating with said counting relays for selecting link circuits corresponding in number to the number of impulses 20 transmitted by said sender.
7. A circuit controlling device comprising a series of counting relays, a number of selectable link circuits controlled by said relays, an impulse circuit for energizing the
- relays in succession a plurality of times, 25 means whereby each relay after having been operated is deenergized in response to the impulse energizing the next relay of the series and a plurality of transfer relays, certain of said transfer relays cooperating with 30 an operated counting relay at certain stages of the selection for selecting the link circuit corresponding to the number of impulses transmitted to said impulse circuit.
8. In a telephone system, an impulse 35 sender, a selector comprising a set of counting relays, a number of selectable lines, means for successively energizing the relays of said set a plurality of times, a plurality of transfer relays, and means for actuating 40 a different transfer relay after each operation of the counting relay set for selecting said lines.

In witness whereof I hereunto subscribe my name this 17th day of December, A. D., 45 1920.

SAMUEL B. WILLIAMS, JR.
